UNITED STATES PATENT OFFICE

164,268

POPCORN MAKING MACHINE

Samuel M. Waas, Kansas City, Mo., assignor to
Manley, Inc., Kansas City, Mo., a corporation
of Missouri

Application May 14, 1951, Serial No. 15,160

Term of patent 14 years

(Cl. D81—10)

To all whom it may concern:

Be it known that I, Samuel M. Waas, a citizen of the United States, residing at Kansas City, in the county of Jackson, and State of Missouri, have invented a new, original, and ornamental Design for a Popcorn Making Machine, of which the following is a specification, reference being had to the accompanying drawing, forming a part thereof, wherein:

Fig. 1 is a front perspective view of a popcorn making machine showing my new design; and

Fig. 2 is a rear perspective view thereof.

I claim:

The ornamental design for a popcorn making machine, as shown.

SAMUEL M. WAAS.
